Attorney

UNITED STATES PATENT OFFICE.

JOHN REID, OF NEW YORK, N. Y.

FURNACE-FRONT AND ADAPTER-RING THEREFOR.

1,300,876.

Specification of Letters Patent. Patented Apr. 15, 1919.

Application filed January 10, 1918. Serial No. 211,143.

To all whom it may concern:

Be it known that I, JOHN REID, a subject of the King of Great Britain, and resident of 17 Battery Place, in the city of New York, in the State of New York, in the United States of America, have invented certain new and useful Improvements in Furnace-Fronts and Adapter-Rings Therefor, of which the following is the specification.

The invention relates to improvements in furnace fronts and adapter rings therefor, as described in the present specification and illustrated in the accompanying drawings that form part of the same.

The invention consists essentially of the novel means employed for standardizing furnace fronts.

In marine boilers of the well known internally fired return tube or so-called "Scotch" type, cast iron fronts are attached to the circular furnace mouths. These fronts carry the coaling doors, and where forced draft is used there are air chambers 25 and valves for regulating the supply of air over the fire, and also side valves for regulating the air supply to the ash pits.

Manufacturers of Scotch boilers have a variety of methods of fitting the furnaces 30 into the front plates, some preferring to flange the front boiler plates out, others flange them inward, and some even flange the furnace mouths over circular holes cut in the boiler front plate. It follows that 35 to make a proper joint between front and furnace, and to take care of different diameters of furnaces and the variety of arrangements by which they are fitted to boiler front plates, many different forms of fronts 40 have to be cast.

Also in a Scotch boiler with three furnaces equipped with forced draft there would be special fronts for the wing furnaces, and others for the center furnace. 45 This leads to confusion, and has hitherto prevented efforts to standardize these furnace fronts, in spite of the fact that in most respects all fronts are alike in construction, except as to their peripheries, where the attachments of the fronts to the furnace are made.

It will be thus seen that the objects of my invention are to devise a front and adapter, that will enable the engineer to

accommodate a front from a stock lot to 55 any boiler, marine or land, within reason, that is to say, a standardized front for a type of boiler, in which considerable variations occur in the many makes, to facilitate the replacement and installation of furnace 60 fronts, and generally to provide a furnace part, which will insure economy and serviceability.

In the drawings, Figure 1 is a vertical sectional view showing the application of 65 the invention in one form.

Fig. 2 is a vertical sectional view showing another form.

Fig. 3 is a vertical sectional view showing another form.

Fig. 4 is a vertical sectional view showing another form.

Fig. 5 is a vertical sectional view showing another form.

Fig. 6 is a sectional detail of the ring secured by cap screws.

Fig. 7 is a plan view of the adapter ring showing the annular extension or flange.

Fig. 8 is a longitudinal sectional view of the furnace front showing boiler and fire 80 box structures.

Like numerals of reference indicate corresponding parts in each figure.

Referring to the drawings, the standardized front 1 shown in Fig. 1 of the drawing 85 is made to suit any boiler of the well known internally fired return tube or so called "Scotch" type, in which cast iron fronts are attached to the circular furnace mouths. The said front has the feed opening 2, and 90 the wall 3 below said feed opening is thickened to compensate for the adapter ring 4 thereby avoiding the necessity of inserting a dead plate.

The adapter ring 4 is the main feature of 95 this invention and is shown in Fig. 1 as of disk form, having the enlargement or annular flange 5 at the inner edge, which projects inwardly in the direction of the opening in the furnace structure made to receive the 100 cast fronts and herein termed the furnace mouth and in fitting the ring to the furnace, the said flange 5 is just within the plate wall 6 of the furnace mouth, but clear of said wall and also clear of the baffle plate of the 105 furnace front as shown at 7, said clearances in the one case enabling the ring with the front to be readily inserted in place and in

the other case facilitating the mounting of the ring 4 on the front 1.

The ring 4 is secured to the front 1 by the bolts 9 extending through said ring 4 and 5 the wall 10 of the front.

The ring 4 is rigidly secured to the wall 6 and the latter rigidly secured to the boiler plate 8 and as the front 1 is rigid with said ring, the attachment of the latter constitutes 10 the installation of said front.

The furnace front 1 may be stocked in considerable quantities, as the front plate and fuel passage are practically the same for all and the back plate, so long as it has 15 a plain surface near the edge, applicable to many furnaces with said adapter ring to connect it to the furnace mouth.

The ring 11 in Fig. 2 is slightly modified as the flange 12 corresponding to the flange 20 5 projects inwardly in the direction of the furnace mouth intermediate of the width of the disk ring but nearer the outer edge and the said ring itself projects beyond the furnace front to form an extension thereof and 25 is secured to the plate wall 13 of the furnace mouth, the latter being secured to the boiler plate 14, said ring being secured to the furnace front by the bolts 15.

The ring in Fig. 3 is in angle form that 30 is to say the disk section 16 has the flange 17 approximately equal to the width of the disk section and projecting from the inner edge and secured to the plate wall 18 of the furnace mouth, the latter being secured to 35 the boiler plate 19.

The ring in Fig. 4 is the reverse of the ring in Fig. 3, as the flange 20 projects from the disk section 21 at the outer edge of the latter and engages the plate wall 22 of the

furnace mouth, the latter being secured to 40 the boiler plate 23.

The ring 24 in Fig. 5 is flat with two annular flanges 25 and 26, one at the outer edge and the other at or near the middle, these flanges being shown in contact with 45 the plate wall 27 of the furnace mouth, the latter being here shown in a different position than in the other figures, for it is between the adapter ring and the boiler plate 28.

This adapter ring may be secured to the back plate of the furnace front by cap screws indicated in Fig. 6 by the numeral 29, thereby facilitating the adjustment of the furnace front to the furnace mouth.

Many departures may be made from the construction without departing from the spirit of the invention so long as they are within the claims for novelty following.

What I claim is:

1. In a furnace front comprising a front plate and a back plate, an annular plate of metal having an annular flange projecting from the rear face thereof and fitting to the plate wall of the furnace mouth and said back plate being secured to the front face of said annular plate.

2. In a furnace front comprising a front plate and a back plate, an endless angle bar having a plain front face and rearwardly 70 projecting flange projections and secured on the side of its plain face to said back plate and meeting the plate wall of the furnace mouth on its flanged side.

Signed at New York city this 22nd day 75 of December, 1917.

JOHN REID
